UNITED STATES PATENT OFFICE.

THOMAS W. CAUDLE, OF DAYTON, TENNESSEE.

DRY-PIPE VALVE.

Application filed September 10, 1923. Serial No. 661,922.

This invention relates to a dry valve for use in automatic sprinkler systems, the valve being so constructed and mounted that the water pressure in the main will 5 be held against the air pressure in the sprinkler system until the air pressure is released by the opening of a head in the sprinkler system.

The object of invention is to provide a 10 device having a dry and a wet valve with a trigger arranged between them and designed to hold the water pressure from below against the air pressure on the top valve.

15 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

25 In the accompanying drawings:—

Figure 1 represents a front elevation of a valve embodying this invention.

Fig. 2 is a side elevation thereof.

30 Fig. 3 is a central vertical section.

Fig. 4 is a horizontal section taken on the line 4—4 of Fig. 1; and

Fig. 5 is a bottom plan view of the upper valve detached.

35 The valve embodying this invention comprises a shell-like casing 1 having annular apertured flanges 2 and 3 for connection respectfully with the sprinkler system and the water main.

40 Valve seats 4 and 5 are located in the casing 1 and are preferably constructed of brass and have threaded engagement with the casing. Designed to engage these seats 4 and 5 are two valves 6 and 7 pivotally

45 connected to one side wall of the casing and which are preferably equipped with bronze or composition interchangeable seats ground to a perfect surface to insure a tight joint. These valves open in the same direction and form in the casing 1 chambers 8 and 9 for a purpose presently to be described.

50 A trigger 10 is pivoted to the toe of the lower valve 7 and its free end engages the heel near the hinge of the top valve 6. A turn buckle 11 connects the pointed free

end 12 of the trigger with the body portion 10 thereof and is designed for lengthening and shortening the trigger for a purpose presently to be described.

60 The chambers 8 and 9 have openings in their side walls provided with hinged closures 13 and 14 with gaskets 15 surrounding the openings which they close. These doors 13 and 14 have flanges 16 overlying the outer face of the casing and provided with bolts 17 for securing the closures in fluid-tight engagement with the casing.

65 A priming pipe 18 extends from the lower end of the casing below valve 7 to a point near the center of the casing opening through the casing by means of a branch pipe 19 just above the top valve 6 while a gage 20 extends to the top of the casing so that it may be easily ascertained when 70 the proper amount of priming water is contained in the chamber 8. A drain opening 21 is provided at the lower end of the casing so that the system may be drained after 75 the valve has been tripped and filled with 80 water.

The casing 1 is provided in its rear walls between valves 6 and 7 with an opening 22 with which is designed to be connected a small water motor, not shown, which is set 85 in motion and turns an alarm when the system is filled with water.

An angle valve 23 is located in pipe 18 for controlling the passage of water through the pipe 18.

90 The top valve 6 is provided on its lower face with a rack 24 extending transversely thereacross and with which the pointed end 12 of the trigger 10 is designed to be engaged in a manner presently to be described.

95 In the use of this device the casing with the two valves located one above the other is inserted between the sprinkler system and the water main and connected to them with fluid-tight joints.

100 The chamber 8 is designed to contain from eight to ten inches of water which rests on the valve 6 before air is pumped into the sprinkler system. After the system has been pumped full of air to a pressure of from twenty-five to thirty pounds the trigger 10 is set rigid against the upper valve 6 and tightened by means of the turn buckle 11 so that a perfectly tight joint between the valve 7 and its seat will be formed. After the 105 parts have been so arranged water from the main is turned on and exerts its pres-

- sure against valve 7 ready to open said valve when the air pressure in the system is reduced which occurs when the heat from a fire releases a sprinkler head. It is of course understood that the air pressure in this instance holds valve 6 seated against the pressure exerted by the trigger 10 from valve 7 and immediately the air pressure is released the valve 6 will open and permit valve 7 to also open under the pressure of the water in the main thus admitting the water to the system which will pass out through the sprinkler on to the surrounding area and thus extinguish the fire.
- 15 After the fire has been extinguished the water from the main is cut off, the casing drained out in the manner above described and the valves set ready for the next fire.
- 20 Various changes in the form, shape, proportion and other minor details of construction may be made without departing from

the principle or sacrificing any of the advantages of the claimed invention.

I claim:—

A valve of the class described comprising 25 a casing, superimposed valve seats within the casing, valves adapted to engage the valve seats to cut off the passage of fluid through the casing, said valve members being arranged one above the other, the upper valve 30 member having a rack formed along its under surface, an adjustable latch member carried by the lower valve member and adapted to engage the rack to adjustably connect the valve members, and said valve members 35 adapted to move to their open positions by water pressure directed to the under surface of the lower valve member.

In testimony that I claim the foregoing as my own, I have hereto affixed my signature,

THOMAS W. CAUDLE.
